US00D958775S

(12) **United States Design Patent** (10) **Patent No.:** **US D958,775 S**
(45) **Date of Patent:** **** Jul. 26, 2022**

(54) **EARPHONE**

(71) Applicant: **BEIJING XIAOMI MOBILE SOFTWARE CO., LTD.**, Beijing (CN)

(72) Inventors: **Hongyu Chen**, Beijing (CN); **Long Chen**, Beijing (CN)

(73) Assignee: **BEIJING XIAOMI MOBILE SOFTWARE CO., LTD.**, Beijing (CN)

(**) Term: **15 Years**

(21) Appl. No.: **29/735,451**

(22) Filed: **May 21, 2020**

(30) **Foreign Application Priority Data**

Nov. 25, 2019 (CN) 201930652269.1

(51) LOC (13) Cl. **14-01**

(52) U.S. Cl.

USPC **D14/223**

(57) **CLAIM**

The ornamental design for an earphone, as shown and described.

DESCRIPTION

FIG. 1 is a front view of an earphone showing our new design;

FIG. 2 is a back view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof;

FIG. 8 is a front, right-side perspective view thereof showing the earphone used in pairs; and,

FIG. 9 is a back, left-side perspective view thereof showing the earphone used in pairs.

The broken lines shown in the drawings illustrate portions of the earphone and form no part of the claimed design.

The broken lines shown in the drawings depict environmental subject matter and form no part of the claimed design.

1 Claim, 9 Drawing Sheets
